UNITED STATES PATENT OFFICE.

JOHN M. DINKINS AND FRANKLIN BUSCH HAYS, OF INDIANAPOLIS, INDIANA, AS-
SIGNORS OF FIFTY-THREE AND ONE-THIRD ONE-HUNDREDTHS TO WILLIAM L.
TAYLOR, OF INDIANAPOLIS, INDIANA.

MAGNETO.

1,014,622.

Specification of Letters Patent.

Patented Jan. 9, 1912.

Application filed November 4, 1909. Serial No. 526,271.

To all whom it may concern:

Be it known that we, JOHN M. DINKINS and FRANKLIN BUSCH HAYS, citizens of the United States, residing at Indianapolis, in the county of Marion and State of Indiana, have invented certain new and useful Improvements in Magnetos, of which the following is a specification.

This invention relates to improvements in magneto-generators for developing an electric spark for explosive engines, and the object of the invention is to greatly increase the spark-generating power of the magneto over those of the same size now in use and 15 to maintain a uniform spark at all of the varying speeds at which the engine may be run.

Another object is to permit the armature to lag while passing through the magnetic field of force, and to cause it to recover its normal travel at the instant when the reversal of polarity is taking place in order to generate a greater volume of current at a low speed than would be generated by a 25 uniform travel of the armature, and thus insure a good spark when the engine is started by means of its crank.

The object also is to provide a magneto which will generate its spark with an equal 30 efficiency regardless of the direction of rotation of its armature, and so as to suit the conditions of any engine.

The object also is to eliminate brush contact by taking the current off of the journal 35 bearings, and the object also is to inclose the armature and magnets in a dust- and wafer-proof case which will occupy but little space and which can be placed in almost any unoccupied position that is convenient.

40 A further object is to so construct the parts that the magnetic field may be shifted forward or backward, following the armature, to cause the spark to occur sooner or later with relation to the action of the piston of the engine without any undue waste 45 of magnetic force.

The object further is to so construct the 50 parts that they may be changed and renewed without expert adjustment and to simplify and cheapen the construction in various ways which will be hereinafter fully described and pointed out in the appended claims.

We accomplish the objects of our inven-

tion by the mechanism illustrated in the accompanying drawings, in which—

Figure 1 is a top plan view of our improved magneto. Fig. 2 is a vertical section of same on the line 2—2 of Fig. 1. Fig. 3 is a transverse or horizontal section on the line 3—3 of Fig. 2. Fig. 4 is a like section on the line 4—4 of Fig. 2 and Fig. 5 is a like section on the line 5—5 of Fig. 2 in which the lines of force are diagrammatically represented by the arrows.

Like characters of reference indicate like parts throughout the several views of the drawings.

6 represents the bedplate of an explosive engine, in connection with which our magneto is used to ignite the hydrocarbon agent, 7 is the engine shaft, and 8 is a worm mounted on the shaft 7 and meshing with a worm wheel 9 on the lower end of the armature shaft 10 of our magneto. The magneto 70 and its parts are supported by a bracket 11 which is secured in any suitable manner to the bedplate 6 of the engine. The shaft 10 is mounted within a substantially cylindrical housing 12 and at the lower end of this 75 housing is a suitable ball bearing journal in which the shaft 10 rotates. The upper end of the housing 12 is expanded, and this expanded portion has an upper annular flange 13 upon which the cylindrical walls 14 of 80 the magneto casing are telescopically mounted in the manner clearly shown in Fig. 2. The cylinder 14 is externally screw threaded at its upper and lower ends to receive the internally threaded coupling rings 85 15. The coupling rings 15 have inturned annular flanges to engage and hold the adjacent parts which are to be united to the cylinder walls 14 by said rings. Within the 90 cylindrical walls 14 the magnets and armature of our magneto are mounted. Our permanent magnets are in three sections 16 (see Fig. 2) which are insulated from each other as shown at 17. These magnets are nearly 95 complete annular disks, as clearly shown in Fig. 5, and are provided with soft iron pole-pieces, the inner walls of which cover an arc of 90 degrees and are mounted within the magnets, diametrically opposite each other as shown in Fig. 5. The pole-pieces 100 17 are held at a distance from the magnets 105 to form an air gap 18 and are provided with extensions 19 which contact with the

inner cylindrical sides of the magnets 16 to which they are clamped by a pair of brass plates 20 and 21 and screws 22 in the manner clearly shown in the drawings. The opposite edges of the pole-pieces are connected and supported by a bridge 23 of brass. The clamp-plates 20 and 21 serve to unite the pole-pieces 17 with the ends of the magnets, and they also serve to unite the magnet sections. Plates 25 and 26, preferably of brass, are placed in contact with the upper and lower faces of the magnets and are secured in those positions by screws which enter suitable holes 27 in the extension 19 of the pole-pieces and in a suitable lug of the bridge plate 23. The lower plate 25 is provided with a handle extension 29 which extends through a slot in the expanded top of the housing 12 to the outside so as to be manually accessible for rotatively adjusting the magnets in order to vary the time of the spark in the cylinders of the engine.

The upper plate 26 is provided with an annular drum-like flange 30 which forms a housing for parts which will be hereinafter described. Mounted within the drum 30 are the races and balls of a ball bearing similar to that at the lower end of housing 12 for shaft 10, previously referred to. This is to support the upper end of the armature.

Our armature is comprised of a series of soft iron plates 31 which are preferred for the purpose of reducing the heat tendencies and for increasing the electrical output, as is well known, and these plates are assembled between larger soft iron members 32 and all of the parts are united by screw bolts 33. This comprises the armature core of the usual H or shuttle type with the exception that the members 35 are thickened so as to form blunt edges 36 which allows a greater magnetic flux to flow through the core of the armature at the time of the reversal of polarity which generates an electrical wave of greater intensity although of shorter duration. In the advance and retard of the spark this wave itself is varied as to time by shifting the magnets by means of the handle 29.

It is because of the above described peculiar construction of our armature, and also of the pole-pieces of our magnets that we are able to maintain a uniform spark at all of the varying speeds of the engine. It is well known that the magnetic readjustment of the molecules of the pole-pieces is resisted by the friction caused by the natural cohesion of the molecules and that this cohesion causes an appreciable magnetic lag. We take advantage of these natural conditions by connecting the ends of the magnets with an adjacent edge of the respective pole-pieces (here shown by the extension 19) which, as the armature approaches the pole-pieces from the direction of said extension

19 causes the magnetic rearrangement of the molecules of the pole-pieces to begin at the extension 19. From long observation of what takes place here in our magneto, the following appears to be true: that owing to the molecular cohesion and friction the magnetic rearrangement is resisted so that when the molecules at and near the edge 19 are magnetically rearranged these at the opposite edge of the pole-piece have not responded, and if the travel of the armature is sufficiently rapid, as when the engine is going at a high speed, it will pass by without allowing sufficient time for the magnetic readjustment of those remote molecules, and the resulting current which would otherwise be proportionately increased with the increase in speed of the armature will remain of uniform and normal volume.

We have found by actual use and observation that the above results are assisted by providing a torque in the armature-shaft which will permit the armature to be held back by the magnetism until forced forward by the resiliency of a spring which will add its force to the constant drive from the engine and cause the armature to fly past the remainder of the pole-piece with accelerated speed.

We have shown in Fig. 2 one means of accomplishing the above result, which consists in making the shaft 10 in two transversely divided parts with a reduced end of one part entering a socket in the other, and a spirally wound spring 38 surrounding the two parts and having an end of the spring fastened to each of the two parts of the divided shaft. By thus making the armature-shaft 10 in two parts we are able to move the upper part on which the armature is mounted while the lower part remains unmoved, as when the engine is not running, by manually operating the handle 29. This moves the magnets and the armature will follow by magnetic attraction until the tension of the spring 38 overcomes the magnetic influence when the armature will be quickly freed from the magnets by the force of the spring, thereby generating a current which will ignite a charge under compression in a cylinder of the engine and thus obviate the usual necessity of cranking the engine by hand in order to start it.

The low tension current from the armature winding passes through a conductor 39 to a sleeve 40 of metal in electrical contact with the upper ball-race. This upper ball-race and sleeve are insulated from the body of the machine as clearly shown in Fig. 2 but are in electrical contact with a metal plate 125 which is connected by a wire conductor 42 with one terminal of the primary, and also one terminal of the secondary winding of an induction coil or transformer 43. The other terminal of the primary winding of

the transformer 43 is in connection with the circuit breaker through the conductor 44, spring-bar 45 (see Fig. 4), and insulated terminal 46 of the circuit-breaker. This terminal 46 has a platinum contact with a like contact point of the other member 47, which member 47 is grounded with the body of the machine. The circuit is completed through the body 32 of the armature which is connected at 48 (see Fig. 2) with the other terminal of the armature winding.

The member 47 of the circuit breaker is a lever which is pivoted at 50 and has a lug 51 which extends through the casing in which the mechanism of the circuit-breaker is mounted, into the path of the bent ends 52 of a rotary and diametrically mounted arm on the sleeve extension 53 of the armature, whereby the circuit is broken twice at each revolution of the armature at the maximum point of intensity of the electrical impulses which are being generated. The lever 47 is held normally in contact by means of a spring 54. A condenser 56 (see Fig. 2), is bridged across the terminals of the circuit-breaker, one of its terminals being grounded to the machine at 57 and the other terminal being connected at 58 with the spring-bar 45. The purpose of this condenser is to intensify the inductive influence in the secondary winding, and to reduce sparking between the platinum contacts of the circuit-breaker. Wound upon the soft iron core 30 is the primary winding of a transformer 43 and outside of this primary winding is the secondary or high tension winding of smaller wire one terminal of which is connected by the wire conductor 42 with the upper journal-bearing of the armature as previously described, and the other terminal of the secondary winding is connected with a spring-conductor 59 which is in electrical contact with the binding post 60.

The binding post 60 is connected by the conductor 61 with a binding post 62 of a distributor mounted in the cap of our machine. This binding post has a stem 63 which is pressed by a spring 64 into constant contact with a spring-plate 65, the outer end of which plate 65 is made to sweep the segments 66 mounted on the inner side of the cap 67. The cap 67 is a non-conductor while the segments are conductors the area of which is shown by dotted lines in Fig. 1. These segments are electrically connected with the binding posts 68 from which the current is conducted to the engine cylinders in the usual manner.

We will now describe the mechanism by which the travel of the spring plate 65 is timed to transmit a broken current to the proper terminals of a four or of a six cylinder engine. It is understood from what has been said that the circuit is broken twice for each revolution of the armature, so that

for each complete sweep or circuit of travel of the spring plate 65 against the four segments 66 in circuit with the four engine cylinders, the armature must have made two complete revolutions. To accomplish this requirement mechanically we provide a spur wheel 72 which is here shown as having its arbor 73 revolubly inserted within the hollow sleeve 53 of the armature, where its notched lower end is locked by engagement with a cross bar 74 to cause the gear wheel 72 to rotate with said armature. The wheel 72 is mounted within a gear case 75 having circular walls, and also mounted in said gear case is a ring 77 with internal cogs. This cogged or toothed ring 77 is just twice the diameter of the wheel 72, and the latter is drivingly connected with said annular gear by the intermediate pinions 78. It is thus obvious that the ring 77 will rotate once for each two revolutions of the spur wheel 72. Mounted in a fixed, but removable manner on the toothed ring 77 is a plate 79 and upon this plate a block of insulation 80 is mounted and upon the block is the spring bar 65. By the above arrangement the bar 65 will make one complete revolution or sweep at each two revolutions of the wheel 72 and its armature. Now, by mounting the two intermediate pinions 78 on a ring 82 which may be released by removing the holding screws 83, said ring, being mounted in a suitable groove in the bottom of the gear case, and by locking the ring 77 to the wall of the gear case by inserting a screw in the hole 86 (see Fig. 3) and by also releasing the plate 79 from the ring and securing the plate to the lugs 84 of the ring 82, the intermediate pinions 78 when rotated by the gear 72 will rock back on the toothed ring 77 to a certain extent so that the resulting forward travel of the plate 79 will amount to one complete revolution to each three revolutions of the armature. Six electric impulses or sparks will be developed under this last adjustment, at each revolution of the plate 79, and therefore of the spring plate 65 carried by it. These impulses will be evenly distributed to six segments in the insulated cap 67 and thence to the respective cylinders of a six cylinder engine. The drawing shows a cap with binding posts and segments for a four cylinder engine and for a six cylinder engine this cap will have to be replaced by one having six segments and a corresponding number of binding posts.

The relation of one half diameter between wheel 72 and internally toothed ring 77 will cause the plate 79 carried by ring 77, and its spring bar 65, to make one complete revolution for every two revolutions of the wheel 72, when the plate 79 is fastened to the ring 77 and the latter is free to move independently of the case in which it is mounted; but when the ring 77 is held

105

110

115

120

125

130

against rotation by being fastened to its case and the plate 79 is released from the ring 77, but is fastened to the ring 82 on which the intermediate pinions 78 are mounted, 5 there will be a loss in the advancement of the plate 79, which will require the ring 72 (and the armature to which it is attached) to make three complete revolutions for each single revolution of the plate 79. Consequently, 10 with our magneto, six electric impulses will be developed during each revolution of the plate 79, and by providing a cap with six segments and six binding posts, six cylinders may be connected and sparked 15 with the same efficiency as four would be under the conditions herein first described.

It will be noted that our magneto is put together with coupling rings throughout, and that all of the parts are readily detachable so as to permit of ready access without special tools whereby even an inexperienced person will be able to renew worn or broken parts. It will also be noted that our magneto is housed in a casing which 25 is practically dust and water-proof, thus eliminating many of the troubles due to those agencies in other magnetos, and it will also be noted that all parts of our apparatus are assembled in a compact and convenient manner, and while we have shown our preferred embodiment of our invention as now known to us, we do not desire to be limited to the exact construction and arrangement of parts here shown and described by us, but

What we claim as new and wish to secure by Letters Patent, is—

1. An electric spark producing apparatus comprising a magnet having a magnetic field, an armature in said field, means for moving said field, means for producing a torque upon the armature by the movement of the field which will overcome the attraction between the armature and field and move the armature to generate electricity.

2. An electric spark producing apparatus comprising a magnet having pole-pieces, an armature between said pole-pieces, means for manually moving the magnet, means for producing a torque upon the armature by the movement of the magnet which will overcome the attraction between the armature and magnet and move the armature to generate electricity.

3. An electric spark producing apparatus comprising a magnet having pole-pieces which are segments of a cylinder connected at one of their ends with the poles of the magnet and separated by an air-gap from the magnet for the remaining major portions of said pole-pieces, means for manually moving the magnet, an armature between said pole-pieces, and resilient means for producing a torque upon the armature by the movement of the magnet which will

overcome the magnetic attraction between the magnet and armature and move the armature.

4. An electric spark producing apparatus comprising a magnet having a magnetic field, an armature in said field, means for moving said field, means for producing a torque upon the armature by the movement of the field which will overcome the attraction between the armature and the field and move the armature to generate electricity, said armature having a core of the shuttle type, the heads of which are thickened on their sides to form blunt longitudinal edges to increase the magnetic attraction between the armature and magnet and thereby increase the torque.

5. An electric spark producing apparatus comprising a magnet having separate pole-pieces which are segments of a cylinder connected at one of their ends with the ends of the magnet and separated by an air-gap from the magnet for the remaining major portions of said pole-pieces, means for manually moving the magnet, an armature rotating between said pole-pieces having a core of the shuttle type, the heads of which core are thickened uniformly on their sides to form blunt longitudinal edges, and resilient means for producing a torque upon the armature by the movement of the magnet which torque will eventually move the armature at starting.

6. An electric spark producing apparatus comprising a magnet having pole-pieces which are segments of a cylinder connected at one of their ends with the ends of the magnet and separated by an air-gap from the magnet for the remaining major portions of said pole-pieces said magnet also having a handle for manually shifting its positions, an armature rotating between said pole-pieces, a shaft on which said armature is mounted said shaft being in two transversely divided parts and resilient means for connecting said shaft-parts to produce a torque upon the armature by the movement of the armature when the magnet is moved by means of said handle whereby the torque will eventually move the armature at starting.

7. An electric spark producing apparatus comprising a rotary movable magnet having a handle for manually moving said magnet, an armature rotating between the poles of the magnet, a shaft on which said armature is mounted, said shaft having resilient means to permit the producing of a torque on the armature when the magnet is moved by its handle and to move the armature with accelerated speed at starting.

8. An electric spark producing apparatus comprising a rotary movable magnet having a handle for manually moving said magnet, an armature rotating between the

poles of the magnet, a shaft on which said armature is mounted said shaft being in two transversely divided parts, a spring connecting the two parts of the shaft to permit the 5 producing of a torque upon the armature when the magnet is moved by its handle and to move the armature with accelerated speed at starting.

9. An electric spark producing apparatus comprising a rotary movable magnet having a handle for manually moving it, an armature rotating between the poles of the magnet, resilient means in the armature shaft which will permit the armature to be 10 moved by the movement of the magnet thus producing a torque by putting said resilient means under tension, to produce a good spark at starting.

10. An electric spark producing apparatus comprising a rotary movable magnet having a handle for manually moving it, an armature rotating between the poles of the magnet having a core with inwardly thickened heads forming longitudinal blunt edges, a shaft on which said armature is mounted said shaft being in two transversely divided parts and resilient means connecting the two parts of the shaft to permit the 15 armature to be moved by the movement of the magnet thus producing a torque by putting said resilient means under tension, to produce a good spark at starting.

10. An electric spark producing apparatus comprising a rotary movable magnet having a handle for manually moving it, an armature rotating between the poles of the magnet having a core with inwardly thickened heads forming longitudinal blunt edges, resilient means in the armature shaft which will permit the armature to be moved by the movement of the magnet thus produc- 20

ing a torque by putting said resilient means under tension, to produce a good spark at starting.

11. An electric spark producing apparatus comprising a rotary movable magnet having a handle for manually moving it, an armature rotating between the poles of the magnet having a core with inwardly thickened heads forming longitudinal blunt edges, a shaft on which said armature is mounted said shaft being in two transversely divided parts and resilient means connecting the two parts of the shaft to permit the 25 armature to be moved by the movement of the magnet thus producing a torque by putting said resilient means under tension, to produce a good spark at starting.

In witness whereof, we have hereunto set 30
our hands and seals at Indianapolis, Indiana, this, 16th day of October, A. D. one thousand nine hundred and nine.
